GARBAGE DISPOSAL UNIT

Carl D. Russell, Muskogee, Okla.

Application February 17, 1950, Serial No. 144,738

7 Claims. (Cl. 146—122)

1

This invention relates to improvements in waste disposal apparatus, and more particularly to an improved kitchen waste or so-called garbage disposal unit designed especially for home use but which can be readily adapted for hotel and restaurant use.

As is well known, the popular types of garbage disposal units now in use are electrically driven and usually employ a high speed cutter disc acting to reduce kitchen waste with a shredding action. With certain forms of kitchen waste, the reduced shreddings may take the form of relatively long filaments which do not readily pass through the waste pipe to sewer, with the result that stoppages are likely to occur. Due to the high speed rotation of their cutting or shredding discs, such units are noisy in their operation and, being electrically driven, they are also susceptible to being put out of operation due to motor failure and they moreover require frequent servicing. The electrically driven disposal unit can also provide a source of electrical shocks to users touching the sink or unit with wet hands, as where the "hot" side of the motor has become accidentally grounded to the sink.

Generally stated, it is the object of the present invention not only to provide a kitchen-waste or garbage disposal unit which avoids the aforementioned objects and disadvantages of the prior electrically driven garbage disposal units of modern design, but also to provide such a unit having superior garbage reducing action, as well as one that is capable of being more economically operated than the prior units.

A more detailed object of the invention is the provision of a hydraulically powered garbage disposal unit which employs water at city pressure both as a source of power and as a flushing medium.

Yet another object of the invention is the provision of a hydraulically driven garbage disposal unit characterized by a low speed, high-power crushing or reducing action, and which is substantially noiseless in its operation.

A further object of the invention is the provision of a garbage disposal unit which may be inexpensively constructed and which, being operated by water at city pressure that is subsequently used as a flushing medium, may be operated more economically than the prior units which employ house water only as a flushing medium and thus require an additional source of power for driving purposes.

A still further object of the invention is the provision of a garbage disposal unit which may

2

be simply and readily installed by connecting the same into a sink waste pipe and to a house water supply line.

Yet another object of the invention is the provision of novel kitchen waste or garbage reducing means which effects reduction of the garbage to a flowable mass through a progressive crushing, cutting-into-short-length, and a final shearing-off action, and which is moreover self-cleaning.

10 A still further object of the invention is to provide a garbage disposal unit characterized by a novel arrangement and assembly of a reciprocating fluid pressure (water) motor, rotary cutting cylinders, and a transmission mechanism for translating reciprocatory travel of the motor piston into low speed rotation of the cylinders capable of developing high cutting and crushing torques, and wherein the exhaust from the motor is supplied to the cutting cylinders for flushing the same.

The above and other objects and advantages of the invention will be seen from the following detailed description, taken with the accompanying drawings showing one physical form of garbage disposal unit constructed in accordance with the invention and giving excellent results in service, wherein:

Fig. 1 is a side elevation, with certain parts broken away, of the improved garbage disposal unit of the invention;

Fig. 2 is a section taken along line 2—2 of Fig. 1, illustrating the details of the transmission mechanism and the water connection between motor unit and reducing means for directing the motor exhaust to the reducing means for use as a flushing medium therefor;

Fig. 3 is a plan view of the cutting cylinders constituting the reducing means;

Fig. 4 is a detail illustrating the construction and mounting of the cylinder cutter bars;

Fig. 5 is a part-diagrammatic view illustrating the inter-meshing relation and the progressive crushing, shearing-off, and self-cleaning action of the cutter bars of the cutting cylinders; and

Fig. 6 is an enlarged section illustrating the action of a cutter bar and a cutter ring in cutting the garbage or waste into short lengths.

In the drawings, wherein like reference characters designate like parts throughout the several views, a garbage disposal unit according to the invention generally comprises a fluid pressure motor unit generally designated MU which employs water at city pressure as its motive fluid, a transmission mechanism generally designated TM for converting reciprocatory travel of the motor

piston to positive, uni-direction rotation of each of a pair of shafts mounting the reducing means in direction opposite to that of its companion shaft, and reducing means generally designated RM for progressively crushing, cutting-into-short-lengths, and shearing-off the waste or garbage supplied to it. Another feature of the invention resides in the integration of said component mechanisms into a compact installation unit, which may be readily connected into the waste pipe of a kitchen sink and to the house water supply line, and in utilization of the exhaust from the motor unit as a flushing medium serving both to convert the comminuted or reduced garbage to a flowable mass capable of passing through the waste pipe to sewer, and to augment the self-cleaning action of the reducing means.

Now considering the component mechanisms aforesaid in detail, the fluid pressure motor unit MU is shown to comprise a relatively short-length cylinder 10 closed at its ends by heads 11, 12. Mounted to reciprocate in the cylinder is a piston, provided with axial stems 14, 15 which are formed tubular (Fig. 2). The lower stem 14 projects through an externally threaded nipple 11a extending axially from the lower cylinder head 11 and has sliding bearing in the nipple and in a bushing-like union 16 which is threaded on to the nipple, as shown. The stem is suitably packed as at 17 to prevent leakage around the stem in its reciprocatory travel with the piston 13. A water supply pipe 18, threaded into the lower end of the union 16, connects with the house water line, so that water at city pressure is supplied to the bore 20 of piston stem 14.

The piston 13 is adapted to be reciprocated by water at city pressure supplied alternately to the opposite ends of the cylinder via the bore 20 of piston stem 14 and a piston-mounted reversing valve mechanism 30 operating on the principle of that disclosed in my copending application Serial No. 215,950, filed March 16, 1951, but modified so as to be actuatable by a non-compressible fluid such as water. The exhaust from the cylinder end opposite that being supplied with the water acting as the motive fluid is conducted from the cylinder through the piston via a piston-mounted reversible exhaust valve 35, also generally disclosed in my aforesaid application, and the bore 38 of the axial stem 15, the exhaust being thereafter utilized in the manner to be described. Said stem 15 extends through the upper cylinder head 12 and has sliding bearing in an external bushing 40 formed thereon, leakage past the stem being prevented by the packing gland 41.

From the foregoing description, it will be understood that piston travel effects reciprocatory travel of the upper piston stem 15, which is converted to rotary motion by the transmission mechanism MV now to be described. By reference to Fig. 2, it will be seen that the stem projects upwardly beyond the piston an amount corresponding to piston travel, and a cross head 75 is secured to the projecting end of the piston stem 15 as by a cap nut 76. Reciprocation of the cross head is transmitted to a main drive head 77 by connecting rods 78, 78a which extend upwardly between the outer ends of the cross head 75 and the main drive head 77, which latter is vertically arranged.

By reference to Fig. 1, the drive head illustratively comprises two spaced plates 80, 81 of rectangular shape as shown in Fig. 2, and which

are securely held in spaced relation by spacing studs 82. Said plates are also each provided with a pair of vertically elongated openings 83, 84 for the shafts 85, 86 of a pair of reducing or cutting cylinders to be described. Said shafts are journaled in spaced bearings 87, 88 carried by correspondingly spaced supporting brackets 89, 90 of massive construction, and which may be supported from an annular mounting ring 91 secured against the top face of the upper cylinder head 12.

To convert reciprocatory travel of the piston 13 and its stem 15, and hence of drive head 77, into rotation of shafts 85, 86, said shafts in their portions which pass through the drive head are cut with or otherwise provided with circular ratchets designated 93, 94 whose teeth are oppositely disposed, as seen in Fig. 2. The drive head mounts between its plates 80, 81 outer and inner pairs of pawls, of which the pawls 95, 96 of the outer pair are pivotally suspended from their upper ends by pins 97, 98, and are provided along their inner side edges with ratchet teeth adapted to engage with the teeth of the circular shaft ratchets 93, 94 along their outer peripheries. The pawls 99, 100 of the inner pair are pivotally mounted at their lower ends on pins 101, 102 to extend into the space between the shaft ratchets and are provided along their outer edges with ratchet teeth adapted to engage with the teeth of said shaft ratchets. To insure engagement of the teeth of the inner pair of pawls with the teeth of the shaft ratchets as the drive head is actuated in downward direction, the pawls 99, 100 may be biased outwardly towards the shafts by a double-ended spring 103 coiled intermediate its ends around a mounting pin 104 extending between the drive head plates, and whose free ends are connected to the upper ends of said pawls so as to exercise a spreading action thereon, as shown.

From the foregoing description it will be observed that the cross head 75, drive head 77 and pawl and ratchet mechanism provides a transmission unit for converting reciprocatory travel of the piston into positive, uni-directional rotation of shafts 85, 86, in opposite directions, such being effected by the pawls 95, 96 of the outer pair engaging with the teeth of the shaft ratchets 93, 94 upon upward movement of the drive head, the pawls 99, 100 of the inner pair meantime riding over the teeth of the shaft ratchets, and by said pawls 99, 100 of the inner maintaining the shafts in rotation when the head is actuated in downward direction, the pawls 95, 96 meantime riding over the teeth of the shaft ratchets. Although other means for effecting conversion of reciprocatory to rotary movement may of course be substituted, the described transmission mechanism provides a simple and effective means for achieving the desired result, and in addition has the advantage that it is fool-proof and thoroughly dependable in operation and may be readily serviced. The described transmission is also of advantage in the present unit in that it effects a low-speed powerful rotation of the shafts 85, 86 as required to develop the high turning torques required in a device designed to crush and comminute certain forms of kitchen refuse, such as bones and other hard materials.

Considering now the construction and operation of the reducing means RM, such comprises a pair of inter-meshing cutting cylinders generally designated 110, 111 powered by the shafts 85, 86 and being accordingly driven continuously

thereby in opposite directions. Said cylinders are of cage-like construction, according to which a plurality of axially extending cutter bars 112 are mounted in spaced relation and in circular series between the cylinder end plates 113, 114, which latter are keyed or otherwise connected to the shafts for turning movement therewith. By reference to Fig. 4 which is a typical section through a cutter bar, each said bar comprises a generally rectangular body portion 112a and a tooth 112b which is adapted to project radially outwardly from the periphery of the cutting cylinder. The front face 115 of the tooth portion is rearwardly offset from the front face of the body portion 112a and is inclined forwardly by a slight angle. The rear face 116 of the tooth portion is sloped forwardly by a greater angle of inclination than its front face and thus converges on said front face. Rather than meeting at a point or apex, the rear face merges into a small-width flat surface 117 which connects with the front face 115, and the line of intersection of flat surface 117 with front face 115 defines a sharp cutting edge 118. The rear face 116 of the tooth portion also merges into a small-width flat surface 119 provided at the intersection of said face with the rear face of the cutterbar body portion. The purpose of the flat faces 117, 119 is to provide turning clearance for the intermeshing cutting bars as will be later described. It will be observed that due to the relatively great thickness of the base or root of a cutting tooth shaped as aforesaid, it is buttressed to withstand the high crushing and cutting forces which it is required to exert in acting on solid or hard forms of kitchen waste.

The cutter-bars are supported at their ends in the cylinder end plates 113 and 114 and are also supported intermediate their ends by cutter rings spaced substantially equally from one another and from the cylinder ends, the cutter-bars seating in notches 120 (Fig. 4) formed in the outer circumferential edges of said rings. By reference to Fig. 3, the righthand cutting cylinder 111 is provided with two such cutting rings designated 121, 121a, and the lefthand cutting cylinder 110 is provided with three such cutting rings 122, 122a and 122b, and it will be observed that the latter rings are staggered with relation to the rings 121, 121a. The outer edges of the cutting rings have reverse V-section, and their apices thus define circumferential cutting edges which are spaced from one another along the axial length of the cutting cylinders.

Referring to Fig. 5, illustrating the intermeshing relationship of the cutter-bars of one cutting cylinder with those of the companion cutting cylinder, it will be seen that the depth of interengagement of the cutter-bars is substantially greater than the radial spacing of the circles containing the cutting edges 118 of a cylinder from the cutting edges of the rings of the same cylinder. Accordingly, each of the cutter bars of the righthand cutting cylinder is provided in its tooth portion with three notches designated 123, 123a and 123b which are properly spaced to receive the cutting edges of the three cutting rings 122, 122a and 122b of the lefthand cutting cylinder. Similarly, each cutter bar of the lefthand cylinder is provided in its tooth portion with two notches 124, 124a for receiving the cutting edges of the two cutting rings 121, 121a of the righthand cutting cylinder. Accordingly, the cutting cylinders may intermesh as shown in Fig. 6 without interference between

the cutting rings of one cylinder and the tooth portions of the cutter bars of the other cylinder.

By reference to Fig. 5, rotation of the cutting cylinders results in a progressive crushing and shearing-off action on garbage or similar refuse material entering the throat between the cutting cylinders. In this view, the cylinders are rotating in the direction of the arrows and a cutter bar designated *a* of one cutting cylinder and a next lower cutting bar designated *b* of the other cylinder are shown to be moving in descending arcs towards one another. Their cutting edges 118 bite or cut into the waste, either cutting through the same or drawing the same bodily farther into the throat between the cylinders. As the cutter bars *a* and *b* move further downwardly towards one another to the position of cutter bars designated *a'*, *b'*, they begin to exert their crushing action. When said cutter bars move still further downwardly to the position indicated by the cutter bars *a''*, *b''*, it will be observed that cutter bar *a''* has begun to enter the space between cutter bar *b''* and the next following cutter bar, and that cutter bar *b''* has fully entered the space between cutter bar *a''* and the next advance or lower cutter bar, with the result that the crushing action continues and is approaching its maximum. It will be observed that clearance is being provided between the front face of cutter bar *a''* and the rear outer corner of cutter bar *b''* by the flat surface 119 of the latter cutter bar.

Now assuming that cutter bar *a* has descended to the position of cutter bar designated *a'''*, and cutter bar *b* has descended to the position of cutter bar designated *b'''*, it will be observed that cutter bars *a'''* and *b'''* have begun to move away from one another. Just prior thereto, the cutting edge 118 of cutter bar *b''* has wiped across the rear flat face of cutter bar *a* then in the position of cutter bar *a'''*, and the cutting edge 118 of cutter bar *a'''* is now beginning to wipe across the rear flat face of the cutter bar *b'''*, and finally moves away from said face, the flat corner surface 119 of the cutter bar *b'''* permitting said cutting edge to just clear said corner. Thus, due to the aforesaid wiping action of the blades 118 of the cutter bars of one cylinder on the rear faces of the intermeshing cutting bars of the other cylinder, any material caught between said cutter bars is subjected to a shearing-off action. Accordingly, any refuse or garbage entering the throat is progressively crushed and comminuted and any waste material in or tending to take sheet form when acted upon by the cutter bars is sheared into longitudinal strips of widths no greater than the distance between the cutting edge 118 and the rear plane or flat face of a cutter bar. It will also be observed that due to the substantially full intermeshing engagement of the cutter bars of the cylinders, the latter are substantially self-cleaning. Moreover, any waste material pushed into the interior spaces of the cylinders during the crushing portions of their arcuate movement readily passes from the cylinders due to their open construction and the effect of the flushing water thereon.

The cutting cylinders also function to cut any material moving into the throat between cylinders into short lengths, due to the entry of cutting edges of the cutting rings of one cutting cylinder into the notches (123, etc., 124 etc.) provided in the tooth portions of the companion cutter bars of the cutting cylinder. This action 75 of the cutter blades and their supporting rings

is diagrammatically illustrated in Fig. 6, wherein it will be observed that the cutting edge of a ring of the lefthand cylinder has knifed itself into its receiving notches in the cutter bar of the companion righthand cylinder, thus to cut any solid material, such as bones and the like to short lengths. The aforesaid action in cutting solid material into short lengths precedes the shearing action of the cutter bars as they begin to move away from one another as previously described, with the result that any solid material is reduced to what may be termed shavings of exceedingly short lengths and width, capable of ready passage through the waste line.

Although in the unit under description, the cutter blades 112 are demountable from the end plates 113, 114 of the cutting cylinders, they may also be formed integral with said end plates and suitably hardened and their cutting edges 118 sharpened, in subsequent hardening and machining operations.

It is also a feature of the invention that the water exhausting from the motor unit MU is employed as a flushing medium. To this end, the cap nut 76 which secures the cross head 75 to the upper piston stem 15 may be formed hollow (Fig. 2) and is provided with two diametrically opposed nipples 125, 126 to which one end of flexible hoses 127, 128 are connected, the hoses at their other end delivering to water passages 130, 131 provided in the unit inlet pipe or tube 134 which is connected at its upper end to the drain opening of a sink, whereby all waste leaving the sink falls into the throat between the cutting cylinders for reduction thereby. Since the water exhausting from the motor unit passes directly to the pipe 134 a substantial volume of flushing water at house line pressure is directed on to the cutting cylinders to flush the same immediately upon the unit being placed in operation, this flushing water serving to augment the self-cleaning action of the cutting cylinders and also converting the reduced garbage or other refuse into a flowable mass capable of passing through the waste pipe to sewer.

It will be understood that the moving parts of the unit are suitably housed, and to this end a cover member 136, secured, for example, to the top of the motor unit, houses the transmission mechanism. Similarly, the cutting cylinders are completely housed within a shell 137, which may be formed integral with the entry pipe 134 and which terminates at its lower end in a discharge pipe 138, connected to waste pipe and through which the flowable mass of refuse passes to the waste pipe and thence to sewer.

The illustrated unit has been successfully operated by city water at 15 lbs. pressure, the unit employing an 8" piston operated at the rate of 9 strokes per minute, which, through the transmission mechanism, effects turning of the cutting cylinders at the rate of 2 1/4 revolutions per minute.

Thus, as distinguished from the popular electrically driven waste disposal unit operating at high speeds, the present unit operates at slow speed but with a vastly more powerful crushing action. By actual test, the refuse left by a family of average size is disposed of in a matter of minutes, and the operation of the device is substantially noiseless. Since the motor unit is operated by water at city pressure, which is also used as a flushing medium in electrically powered units, the operation of the present unit is more economical than that of the prior units since the exhaust from the motor is employed as

the power as well as the flushing medium. Moreover, the difficult maintenance problems of the prior garbage disposal units have been reduced to a minimum in the instant unit and, being hydraulically driven, there is no danger of a user of the present unit receiving electrical shocks when touching the sink or unit with wet hands.

The present application is a continuation-in-part of my earlier application Serial No. 73,773, filed January 31, 1949, now abandoned.

As many changes could be made in carrying out the above construction without departing from the scope of the invention, it is intended that all matter contained in the above description or shown in the accompanying drawings shall be interpreted as illustrative and not in a limiting sense.

I claim:

1. In waste disposal apparatus, waste reducing means comprising a pair of rotary intermeshing cutting cylinders arranged with their axes parallel, each including a plurality of cutter bars extending lengthwise of the cylinder and being circumferentially spaced about the periphery thereof an amount corresponding substantially to the overall cutter-bar width whereby the cutting bars of the cylinders may intermesh, said cutter bars comprising a body portion and a tooth portion protruding radially outwardly therefrom, said tooth portion being offset rearwardly from the front face of the body portion and being forwardly inclined and terminating in a cutting edge.

2. In waste disposal apparatus, waste reducing means comprising a pair of rotary intermeshing cutting cylinders arranged with their axes parallel, each including a plurality of cutter bars extending lengthwise of the cylinder and being circumferentially spaced about the periphery thereof an amount corresponding substantially to the overall cutter-bar width whereby the cutting bars of the cylinders may intermesh, said cutter bars comprising a body portion and a tooth portion protruding radially outwardly therefrom, said tooth portion being defined by front and rear faces which converge to a cutting edge, the front face of the tooth portion being rearwardly offset from the front face of the body portion and being sloped in forward direction.

3. In waste disposal apparatus, waste reducing means comprising a pair of rotary intermeshing cutting cylinders arranged with their axes parallel, each including a plurality of cutter bars extending lengthwise of the cylinder and being circumferentially spaced about the periphery thereof an amount corresponding substantially to the overall cutter-bar width whereby the cutting bars of the cylinders may intermesh, said cutter bars comprising a body portion and a tooth portion protruding radially outwardly therefrom, said tooth portion being defined by front and rear faces which converge on one another and merge into a small-width flat surface connecting said faces, the line of intersection of said front face and said flat surface defining a cutting edge adapted to wipe across the rear face of the body portion of the next lower intermeshing cutter bar of the other cutting cylinder, said rear face merging into a small-width flat surface connecting said face with the rear face of the body portion, said flat surfaces providing for turning clearance of intermeshing cutter bars as they move in descending arcs toward and away from one another.

4. Waste reducing means for waste disposal

apparatus, as set forth in claim 3, wherein the tooth portion of each cutter bar is offset rearwardly from the front face of the body portion thereof and is inclined in forward direction.

5. In waste disposal apparatus, waste reducing means comprising a pair of rotary intermeshing cutting cylinders arranged with their axes parallel and their peripheries in substantial contact, each including a plurality of cutter bars extending from end to end of the cylinder and being circumferentially spaced about the periphery thereof of an amount corresponding to the overall width of said bars and each said cutter bar including a tooth portion extending radially outwardly from the cylinder periphery for movement into the space between the cutter bars of the other cylinder, said cylinders each also including a plurality of cutter-bar supporting rings spaced axially from one another along the length of the cylinder, the outer circular edges of the rings of one cylinder cooperating with the tooth portions of the cutter bars of the other cylinder to cut waste material being acted upon by the intermeshing cutter bars into short lengths.

6. Waste reducing means for waste disposal apparatus, as set forth in claim 5, wherein the supporting rings of one cutting cylinder are staggered axially with reference to the supporting rings of the cylinder.

7. In waste disposal apparatus, waste reducing means comprising a pair of rotary intermeshing cutting cylinders arranged with their axes parallel and their peripheries in substantial contact, each including a plurality of cutter bars extend-

ing from end to end of the cylinder and being circumferentially spaced about the periphery thereof of an amount corresponding to the overall width of said bars and each said cutter bar including a tooth portion extending radially outwardly from the cylinder periphery for movement into the space between the cutter bars of the other cylinder, said cylinders each also including a plurality of cutter-bar supporting rings spaced axially from one another along the length of the cylinder, the outer edges of the rings of one cylinder lying on circles which intersect the arcuate path of movement of the tooth portions of the cutter bars of the other cylinder and said tooth portions being notched to receive said edges thereby to permit turning movement of the cylinders without interference and to effect cutting of the material being acted upon by the intermeshing cutter bars into short lengths.
